UNITED STATES PATENT OFFICE.

SPENCER M. HURTT, OF RIDLEY PARK, PENNSYLVANIA, ASSIGNOR TO THE MYNOL
CHEMICAL COMPANY, A CORPORATION OF DELAWARE.

DESIGN FOR A RECEPTACLE FOR DENTISTS' USE

59,965.

Specification for Design.

Patented Dec. 13, 1921.

Application filed January 7, 1921. Serial No 435,751. Term of patent 14 years.

To all whom it may concern:

Be it known that I, SPENCER M. HURTT, a citizen of the United States, residing at Ridley Park, in the county of Delaware and State of Pennsylvania, have invented a new, original, and ornamental Design for a Receptacle for Dentists' Use, of which the following is a specification, reference being had to the accompanying drawing, forming part thereof.

Figure 1 is a cross sectional view through my design for receptacle for dentists' use; Fig. 2 is a plan view of the lower portion of the article, the cover being removed; and Fig. 3 is a plan view of the complete article.

I claim:

The ornamental design for a receptacle for dentists' use, as shown.
